(57) **CLAIM**

The ornamental design for a handle for a suitcase, as shown and described.

DESCRIPTION

FIG. 1 is a perspective view of a handle for a suitcase showing our new design;

FIG. 2 is a perspective rear view thereof;

FIG. 3 is a front view thereof;

FIG. 4 is a rear view thereof;

FIG. 5 is a right side view thereof;

FIG. 6 is a left side view thereof;

FIG. 7 is an enlarged view of the shaded region shown in FIG. 1 thereof;

FIG. 8 is an enlarged view of the shaded region shown in FIG. 2 thereof;

FIG. 9 is an enlarged view of the shaded region shown in FIG. 3 thereof;

FIG. 10 is an enlarged view of the shaded region shown in FIG. 4 thereof;

FIG. 11 is an enlarged view of the shaded region shown in FIG. 5 thereof; and,

FIG. 12 is an enlarged view of the shaded region shown in FIG. 6 thereof.

The broken lines show a portion of the handle for a suitcase which forms no part of the claimed design. The stipple shading in FIGS. 7-12 shows an overall textured surface.

1 Claim, 12 Drawing Sheets
